GEORGE D. SCHERMERHORN, OF READING, MICHIGAN

CUSHION FOOT

Application filed March 2, 1932. Serial No. 596,263.

My invention relates to a detachable cushion foot particularly adapted for use in conjunction with folding chairs.

An object of the invention is to provide 5 a durable, inexpensive cushion foot which may readily be secured to the extremities of chair legs of various types and which may be inexpensively manufactured in large quantities.

10 A further object of the invention is to so associate the cushioning substance with a metallic foot that there is substantially no possibility of its tearing away therefrom and to so form the metallic foot of a plurality of 15 parts that it is of rigid construction and constitutes a mold about which the cushioning substance may be formed in situ.

Further meritorious features of the invention reside in the particular arrangement and 20 combination of parts to be described herein-after in conjunction with the accompanying drawing wherein like numerals refer to like parts throughout the several figures and wherein:

25 Fig. 1 is a side elevation of a chair utilizing the improved foot structure,

Fig. 2 is an elevation, partly broken away and in section, of the foot positioned at the extremity of a chair leg,

30 Fig. 3 is a section along 3—3 of Fig. 2, and

Figs. 4 and 5 illustrate the composite units forming the metallic foot assembly with which the cushioning substance is associated.

Referring now to the drawing, Fig. 1 illustrates a conventional folding chair including front and rear legs 10 and 12 at the extremities of which are positioned cushioned feet 14 of the improved type to be described hereinafter. Each of the chair legs may comprise a metallic strip 16, the longitudinal edges of which are rolled over into tubular form as illustrated at 18 and 20.

The metallic portion of the cushion foot assembly includes a cap member 22 illustrated in Fig. 5, which cap is elongated as illustrated and provided with a depending flange 24 extending from its peripheral edge. A longitudinal slot 26 is formed in the top of the cap, offset from the center thereof, and 45 extends parallel to the edge thereof throughout a substantial portion of its length.

50 The other metallic element (Fig. 4) comprises a web portion 28 beveled as at 30 across its upper extremity and turned laterally at the base thereof to form a flange 32. As

hitherto stated, the slot 26 is offset from the center of the cap 22 and the width of flange 32 is substantially equal to the distance between slot 26 and the furthest removed edge of the cap 22.

55 The central portion of the edge of flange 32 is cut away in oval formation as illustrated at 34 and apertures 36 and 38, centering upon the turned over portion 40, are provided. A lug 42 is struck outwardly from the web portion 28 and extends parallel to the flange 32. Its width is equal to that of the flange 32 and the upper portion thereof is adapted to seat upon the inside of the cap member 22 as clearly illustrated in Fig. 3. An aperture 60 44 is provided in the central portion of the web 28.

65 In assembling the units the web 28 is inserted from the bottom through longitudinal slot 26 in the cap 22. The web, adjacent its lower extremity, is provided with protrusions 46 and 48 which limit the extent to which the web may be forced through the slot, the protrusions being adapted to seat against the underside of the top of the cap 70 22. It will be apparent that the upper portion of the lug 42 is in alignment with the protrusions 46 and 48, which relationship permits the said lug to seat snugly against the top of the cap. By reason of the oval cut 75 80 away portion 34 the lug 42 may readily be welded to the under face of the cap to form an integral unit.

85 Having associated the metallic elements in the proper relative position some suitable cushioning substance is molded insitu about the flange 32 and within the depending flanges 24 of cap 22. Preferably rubber is utilized and the resulting cushion is clearly 90 illustrated at 50. By reason of the particular position of apertures 36 and 38, the rubber or other substance may readily flow therethrough in both a vertical and horizontal direction. This facilitates the rapid molding of the cushion foot 50, the opening 52 95 provided by the turned up lug 42 assisting in permitting free flow of the rubber during the molding operation.

100 The cushion foot now being complete, it may be readily inserted, due to the beveled upper portion 30 of the web 28, under the edges of the rolled over tubular portions 18 and 20 of the chair legs, the intermediate leg portion 16 in each instance being preferably formed with a slight bulge 54 which 110

cooperates with the aperture 44 to retain the foot assembly in position. The tubular rolls 18 and 20 may be subjected to additional pressure subsequent to insertion of the foot assembly if necessary, although the locking action of the indentation 54 and the aperture 44 will suffice.

Various modifications of the improved structure illustrated herein may be apparent to those skilled in the art and for that reason I wish to limit myself only within the scope of the appended claims.

What I claim:

1. A cushion foot assembly including, in combination, a metallic web provided with a laterally extending flange at one extremity thereof, and an aperture extending through the juncture of the web and flange whereby said aperture provides a vertical and a lateral passage and cushioning material molded about said end above and below said flange.

2. A cushion foot assembly including, in combination, a metallic web provided with a laterally extending flange at one extremity thereof, apertures extending through the juncture of the web and flange whereby each aperture provides a vertical and lateral passage, a cut away portion extending from the outer edge of said flange, and a lug struck outwardly from the web to a position substantially parallel to the flange, and cushioning material molded about said end above and below said flange and between the flange and lug.

3. A chair foot including, in combination, an element comprising a web portion having a flange extending laterally away from one extremity thereof, and a lug struck up from said web portion to provide an opening in the web, said lug extending parallel to said flange and being superposed thereover, and cushioning material molded about said flange and between the flange and lug and extending through the aperture formed by the striking up of the lug.

4. A chair foot including, in combination, an element having a web portion beveled at one extremity, lateral protrusions adjacent the opposite extremity thereof, a cap member having a slotted top and depending flanges positioned over said web portion and seated upon said protrusions, a flange extending laterally away from the extremity of said web portion below said cap, a lug struck from said web in superimposed relation to said flange and adapted to seat against the underside of the top of said cap and cushioning material within the cap about the flange.

5. A chair foot of the class described comprising an element having a web portion and

a laterally extending flange extending away from one extremity thereof and a lug punched therefrom above said flange, apertures extending therethrough and centered at the juncture of said web portion and said flange, a cap member having depending flanges positioned over said web portion and spaced from said flange by said lug, and cushioning substance molded in situ over said flange and the web portion adjacent thereto, said substance being retained within the cap and its depending flanges.

6. A chair foot assembly comprising a unitary metal web having a pair of vertically spaced apart angular flanges adjacent its lower end and an aperture through the web between said flanges and cushioning material molded about the lower end of said web below and between said flanges.

7. A chair foot including, in combination, an element having a web portion beveled at one extremity, a flange extending laterally away from the opposite extremity, a lug struck from said web in superimposed relation to said flange, a cap member having a slotted top and depending flanges positioned over said web portion and seated upon said lug, and cushioning material disposed within the cap about the flange and between the flange and lug.

8. In combination with a chair leg having tubular edge portions, a cushion foot assembly comprising a metal shank having vertically spaced apart laterally projecting portions at one end, said shank provided with apertures between said laterally projecting portions, said shank being beveled at its opposite end for insertion into the tubular edge portions of the chair leg, a flanged cap seated over said shank upon the uppermost of said laterally extending portions, and cushioning material disposed within said cap between the laterally extending portions of the shank and completely surrounding the lowermost of said portions.

9. A chair foot assembly comprising a unitary metal web having a pair of vertically spaced apart angular flanges adjacent its lower end and an aperture through the web between said flanges, a slotted cap seated upon the upper of said angular flanges and provided with a marginal flange extending in the direction of the lower angular flange, and cushioning material molded about the lower end of said web below and between said flanges and within the marginal flange of said cap.

In testimony whereof, I, GEORGE D. SCHERMERHORN, sign this specification.

GEORGE D. SCHERMERHORN.
